(57) **CLAIM**

The ornamental design for a gemstone, as shown and described.

DESCRIPTION

FIG. 1 is a perspective view of a gemstone showing our new design;

FIG. 2 is a left-side elevational view of the gemstone shown in FIG. 1, the right-side being a mirror image thereof;

FIG. 3 is a front elevational view of the gemstone shown in FIG. 1, the rear being a mirror image thereof;

FIG. 4 is a top plan view of the gemstone shown in FIG. 1;

FIG. 5 is a bottom plan view of the gemstone shown in FIG. 1;

FIG. 6 is an alternative perspective view, showing the gemstone of our new design made of a translucent material;

FIG. 7 is a left-side elevational view of the gemstone shown in FIG. 6, the right-side being a mirror image thereof;

FIG. 8 is a front elevational view of the gemstone shown in FIG. 6, the rear being a mirror image thereof;

FIG. 9 is a top plan view of the gemstone shown in FIG. 6; and,

FIG. 10 is a bottom plan view of the gemstone shown in FIG. 6.

The broken lines shown in the drawing are for illustrative purposes only and form no part of the claimed design.
